RAZOR BLADE SHARPENER

Louis C. Hobart, Southington, Conn.

Application August 2, 1933, Serial No. 683,244

13 Claims. (Cl. 51—57)

This invention relates to improvements in razor blade sharpeners, and more particularly to safety razor blade sharpeners.

One object of this invention is to provide a 5 razor blade sharpener or double-edge razor blades, in which a single sharpening member has two spaced sharpening surfaces in permanently fixed or rigid accurate relation to each other so that both edges of razor blades will accurately contact with corresponding sharpening surfaces of the sharpening member.

Another object of this invention is to provide a razor blade sharpener for double-edge razor blades, in which a single reversible sharpening 15 member has two sets of sharpening surfaces on its opposite faces.

Another object of this invention is to provide 20 a razor blade sharpener in which bolts serve both to hold parts of the sharpener assembled together and to position razor blades for sharpening.

Another object of this invention is to provide 25 an electromagnetic razor blade sharpener with cushioning means so forming part of the construction as to minimize or eliminate the transmission of the vibrations of the sharpener to a table or desk on which the sharpener is supported.

Another object of this invention is to provide 30 an electromagnetic razor blade sharpener in which the casing is normally resiliently held spaced above the base and so that when a portion of the casing is depressed, an electric switch is closed.

With the above and other objects in view, this 35 invention includes the improved features, parts and combinations of parts disclosed in the following description, appended claims and accompanying drawings forming a part of this specification.

In the accompanying drawings in which certain ways of carrying out the invention are shown for illustrative purposes:

Fig. 1 is a plan view illustrating an embodiment of the invention;

Fig. 2 is a front elevation of Fig. 1;

Fig. 3 is a left end elevation of Fig. 2;

Fig. 4 is a right end elevation of Fig. 2 with 50 a modified form of sharpening member and illustrating the electric switch in open position;

Fig. 5 is a view similar to Fig. 4 with the switch in closed position;

Fig. 6 is a sectional plan view on line 6—6 of 55 Fig. 2;

Fig. 7 is a sectional, longitudinal elevation on line 7—7 of Fig. 1;

Fig. 8 is a longitudinal sectional elevation on line 8—8 of Fig. 1;

Fig. 9 is a transverse, sectional elevation on 60 line 9—9 of Fig. 2; and

Fig. 10 is a transverse, sectional elevation on line 10—10 of Fig. 2.

In the following description and claims, the 65 various parts of the apparatus and details of the invention will be identified by specific names for convenience, but they are intended to be as generic in their application as the prior art will permit.

Referring to the drawings, the sharpening device 70 comprises a base 20 provided with an upwardly extending portion 21 adapted to slidably enter a case member or casing 22. Holes 23, 24, countersunk in the base 20 at 25, 26, are provided for the reception of flanged bushings 27, 28, preferably of resilient cushioning material such, for example, as rubber. The flanged bushings have central bores to receive bolts 29, 30, the upper ends of which are provided with threads 31, 32 to engage the threaded portions 75 of the bores of the nuts or members 33, 34, which have dome shaped upper portions suitable to enter the positioning holes of a safety razor blade, and polygonal lower portions 35, 36, suitable to be engaged by a wrench. The bolts 29, 30, project slightly through the upper ends of the members 33, 34, so that after final adjustment of the device has been made, the bolt ends may be upset, as by heading or spinning, to provide enlargements 95, 96, whereby the bolts cannot work 80 loose and the device is sealed against tampering.

Coil supporting members 37, 38, preferably of 85 resilient cushioning material, rest on the central flat portions of metal springs 39, 40, which extend within the recesses in the platform 41 of 90 the base 20 to insure proper positioning of the springs. A sheet metal spring member 87, resting on the supports 37, 38, is provided on one side with upwardly bent extensions or ears 42, 43, and on its other side with a single, wide, upwardly 100 bent ear 44. The armature 45 is made of magnetic material such as iron and is attached to the spring ears 42, 43 by riveting or otherwise and extends into position to be acted upon by the core 46 of the coil 47 and is provided with ears 105 48, 49, extending upwardly. The core 46 is formed of laminations of magnetic material such as iron.

A T-shaped member 50 is similarly attached as by riveting to the spring ear 44. A plate 70, constituting the roof or top of the case 22, is 110

provided with openings 51, 52, 53, through which the upwardly extending parts 48, 49, 50, protrude, the openings being of a size to permit free vibratory or oscillatory action of the protruding parts. Notches 54, 55, 56, are provided for the reception of the sharpening member 57 which is preferably a permanent magnet and has beveled edges 58, 59 whereby it is held as in a 3 point suspension by the opposing tensions of the spring 10 ears.

The sharpening member 57 is preferably of hardened steel and has the pair of spaced sharpening surfaces 60, 61 accurately formed at a suitable angle on its upper face to properly simultaneously sharpen one side of both edges of a double edge safety razor blade. To accomplish this properly, the surfaces 60, 61, must be formed at a correct angle and must have their longitudinal axes parallel to each other to a high degree of accuracy. If the axes of the sharpening surfaces are not accurately parallel, the opposite edges of the razor blade will not both rest in proper sharpening position on the sharpening surfaces. By forming the sharpening surfaces on 25 a single relatively rigid member, I am able to both initially form the sharpening surfaces accurately and retain them so indefinitely.

The sharpening member 57 may also be provided on its lower face with a pair of spaced 30 sharpening surfaces 62, 63. If desired, the pair of sharpening surfaces 60, 61 may be made at a suitable angle for an ordinary weight of beard and sharpening surfaces 62, 63 may be made at an angle suitable for a heavy weight of beard. 35 It will be observed that the sharpening member 57 can be readily snapped out of its engagement with the notches in the parts 48, 49, 50 to readily permit of reversing the sharpening member face for face to bring the sharpening surfaces 62, 63 40 into the upper or sharpening position or for renewing, changing or replacing the sharpening member at will.

The modified form of sharpening member 64 illustrated in Figs. 4 and 5 may be formed of 45 sheet metal and is provided with a pair of sharpening surfaces 65, 66. The sharpening member 64 can be snapped into and out of position in the notches in the parts 48, 49, 50 similarly to the sharpening member 57. The sharpening member 64 is provided with only one pair of sharpening surfaces and therefore is not reversible.

To insure proper positioning of the parts, the 50 spring member 87, which may be of brass, is provided with a central, rectangular opening 69 through which a slight projection of the core 46 may extend. In like manner, the roof or top plate 70 is provided with openings 71, 72 through which the bolts 29, 30 pass, whereby the proper spacing 55 of the bolts is insured, and is also provided with a central, rectangular opening 73 through which a slight extension of the core 46 may extend to insure proper positioning of the parts. A coil 47 surrounds the central core 46 and rests 60 on the spring plate 87, the roof plate 70 resting on top of the coil and being held down by the nuts or threaded members 33, 34 and the bolts 29, 30.

The longitudinal spring 39 rests at its central 65 part on the ledge 21 of the base 20, the central portion of the spring having a lateral extension 88 (Fig. 10) adapted to fit a recess in the platform 41 of the base 20 whereby the position of the spring is established. The member 37 resting on 70 the lateral extension 88 of the spring 39 main-

tains the spring in position. The extremities of the spring 39 are curved upward to bear upward against the internal bosses or enlargements 74, 75 (Fig. 6) of the case 22. In like manner the spring 40 rests at its central part on the ledge 21 of the base 20, the central, lateral extension of the spring 39 fitting a recess in the platform 41 of the base 20 whereby the position of the spring is established. The member 38 resting on the lateral extension 89 maintains the spring in position. The extremities of the spring 40 are curved upward to bear against the internal bosses or enlargements 77, 78 of the case 22. A transverse extension 79 of the spring 40 (Figs. 4, 5) rests on an extension 80 of the platform 41, its extreme 80 end forming a switch part or member and being 85 in operative position with relation to the cooperating switch part 76 of the spring 39.

An upwardly extending projection 82 is provided at one end of the case to serve as a push 90 button. Normally, as when the switch is open or off, the parts are in the relative positions shown in Fig. 4 where the open switch gap between parts 76 and 81 is clearly shown. Pressure on part 82, causing downward movement of the corresponding 95 end of the case 22, causes the extension 79 of the spring 40 to rock on the platform extension 80 to cause the switch part 81 to contact with part 76, closing the electric circuit.

An opening 83 is provided at one end or side 100 of the case 22 whereby the conductors 97, 90 may enter the case, one end of these conductors being connected, as by the ordinary connecting plug, with a source of electrical energy. Within the case of the device, the conductor 97 is connected 105 as by soldering 91, to the spring member 39 and the conductor 90 is connected as by soldering 92 with one terminal of the coil winding 47. The other terminal of the coil winding 47 is connected 110 as by soldering 93 with the short conductor 94, the 115 other end of which conductor 94 is connected as by soldering 95 with the spring member 40.

The ledge or platform 21 is cut away at 84 to provide ample space for the conductors 97, 90. The supporting member 38 is provided with a 120 central, transverse opening 85 (Figs. 8, 10) and the armature 45 is provided with an extension 86 (Figs. 6, 8, 10) positioned within the opening 85 whereby the movement of the armature may be limited. For efficient operation, the armature 45 should work as close as possible to the end of the core 46, but preferably should not touch the core as excessive noise results. The opening 85 in the cushioning support 38 acts both to properly limit the approach of the armature 130 toward the core and avoid noise from the armature striking the core or the support 38, since the latter is of rubber or other suitable cushioning material.

By having the bushings 27, 28 and the supporting members 37, 38 of cushioning material—as rubber—the power actuated, vibrating members are “full floating” with reference to the base when in operation. That is, they are not rigidly connected with the base. Contact of the roof or 140 top plate 70 with the case 22 will be broken by depression of the part 82 of the case to operate the starting switch—all contributing to minimizing the noise incident to vibration of operation of the device. The spring member 87 may be 145 convexed (bent upwardly at its central part) and the width and consequent rigidity of the spring ear 44 be made not equal to the sum of the widths of the opposing ears 42, 43, whereupon by tightening the bolts 29, 30, the convexity 150

- of the spring member 87 would be reduced, the members 37, 38 would be compressed and the relative positions of the armature 45 and core 46 would be changed—all contributing to “tuning” 5 the device for proper large amplitude of vibration of armature 45 and sharpening member 57, and compensating for commercial variations of construction and assembly of the parts, and variations of the electrical characteristics of the coils.
- 10 The heads of the bolts 29, 30 engage against the lower cushioning members or bushings 27, 28, with the bolts 29, 30 extending upwardly through openings in the spring member 87, openings in the core 46 (Fig. 6) formed by the short central laminations of the core 46, through openings 71, 72 in the roof or top plate 70, and carry the threaded nuts 33, 34 which latter form portions of the bolts and extend through the openings 67, 68 in the sharpening member 57, which openings 20 67, 68 are elongated to permit free vibratory or oscillatory motion of the sharpening member 57.
- The bolts 29, 30 hold the roof or top plate or limit member 70, coil 47, spring plate 87, the upper cushioning members or supports 37, 38, spring 25 members 39, 40 and the lower cushioning members or bushings 27, 28 all clamped firmly but resiliently to the base 20. It will be observed that the casing or case 22 is spaced on all sides away from the coil 47, thus minimizing the transmission of heat to the case 22, which if made of certain materials would soften if subjected to excessive heat. This air space surrounding the coil 47 becomes heated by the coil and passes up and out of openings 51, 52, 53 in the top plate 70, at the same time being replaced by fresh cool air entering through the opening 83 in the case 22, thus maintaining air circulation which aids in carrying away the heat developed in the coil 47 and its core 46.
- 30 The top plate 70, which is preferably of non-magnetic metal, such as brass, for example, has intimate engagement with the sides of the upper end of the core 46, and aids in carrying heat away by conducting heat away from the upper end of the core 46 and coil 47, the heat being carried away from the plate 70 by radiation and convection.
- The operation of the device is as follows. To establish the desired angle at the extreme cutting edges of a safety razor blade, an abrasive compound, furnished with the device and consisting of a lubricant impregnated with a very fine abrasive, is moistened and applied to the lapping surfaces. The double edge blade is placed with 50 its edges resting on the inclined lapping surfaces 60, 61, the positioning pins passing through the locating holes of the blade. The blade will then be firmly held down by the permanent magnetism of the sharpening or lapping member 57 (or 64), the amount of actual pressure of the blade edges 55 against the inclined lapping surfaces being determined by the magnetic attraction between the blade and sharpening or lapping member. The button like projection 82 of the case is then pressed downward by the user, depressing the corresponding end of the case and causing the 60 switch to close the electrical circuit by contact of the switch parts 76, 81 (Fig. 5).
- Alternating current flowing through the coil 70 47 will set up a magnetic force which reverses as the current alternates. This reversal of magnetic field, apparent at the core 46 of the coil, will act on the vibratory suspended armature 45 to cause it to vibrate, which motion, evident in the upper turned ears 48, 49 of the armature, will cause a 75 vibratory or oscillatory movement of the sharpening or honing member. Since the blade is prevented from participating in this movement by the nuts 33, 34 of the stationary positioning pins or bolts 29, 30, its edges will be rubbed by the abrasive-covered, inclined lapping surfaces of the sharpening member.
- To finish the edges of a blade so treated, the same sequence of operations is followed as for lapping described above, except that the rubbing surfaces of the sharpening member are moistened but no abrasive compound is used, whereby the cutting edges of the blade are burnished.
- The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.
- I claim:
1. A razor blade sharpener comprising: electromagnetic means, spaced vibratory elements, one of which is adapted to be vibrated by said electromagnetic means; a one piece sharpening member interconnecting said vibratory elements and having spaced sharpening surfaces; and fixed 100 razor blade positioning means.
  2. A razor blade sharpener comprising: electromagnetic means; spaced vibratory elements, one of said vibratory elements being adapted to be vibrated by said electromagnetic means; a one piece sharpening member spanning and entirely 110 supported and held by said vibratory elements and having spaced sharpening surfaces; and fixed razor blade positioning means.
  3. A razor blade sharpener comprising: electromagnetic means including an upstanding magnetizable core; spaced vibratory elements, one of said vibratory elements extending lengthwise and outside of said core and having an armature extending transversely of, and located adjacent the lower end of said core; a sharpening member extending transversely of the upper end of said core 115 and spanning said vibratory elements; and fixed razor blade positioning means.
  4. A razor blade sharpener comprising: electromagnetic means; spaced resiliently mounted vibratory elements, one of said vibratory elements being adapted to be vibrated by said electromagnetic means; a reversible one-piece sharpening member having sharpening surfaces on its opposite faces and adapted to reversibly span and be 120 entirely supported and held by said vibratory elements; and fixed razor blade positioning means.
  5. A razor blade sharpener comprising: a base; electromagnetic means; upwardly extending bolts securing said electromagnetic means to said base 130 and also serving to position a razor blade; vibratory means adapted to be vibrated by said electromagnetic means; and a sharpening member carried by said vibratory means and extending transversely of the upper ends of said bolts.
  6. A razor blade sharpener comprising: a base; spacing means on said base; electromagnetic means upon said spacing means and having an upstanding core with a lower core end adjacent but spaced from said base; vibratory means having an armature extending transversely of said core into the space between said base and said lower core end; a sharpening member adjacent the upper core end and actuatable by said vibratory means; and razor blade positioning means.

7. A razor blade sharpener comprising: a base; spacing means on said base and provided with an opening; electromagnetic means upon said spacing means and having an upstanding core 5 with a lower core end adjacent but spaced from said base; vibratory means having an armature extending transversely of said core through said opening and into the space between said base and said lower core end; a sharpening member adjacent the upper core end and actuatable by said vibratory means; and razor blade positioning means. 10 80
8. A razor blade sharpener comprising: a base; cushioning spacing means on said base and provided with an opening; electromagnetic means upon said cushioning spacing means and having an upstanding core with a lower core end adjacent but spaced from said base; vibratory means having an armature extending transversely of 15 said core through said opening and into the space between said base and said lower core end; a sharpening member adjacent the upper core end and actuatable by said vibratory means; and razor blade positioning means. 85
12. A razor blade sharpener comprising: a base; electromagnetic means supported by said base; vibratory sharpening means adapted to be actuated by said electromagnetic means; limit means connected to said base; a casing; electrical connections to said electromagnetic means, including a switch, said switch comprising a pair of spring switch parts extending along opposite sides of said casing and normally resiliently pressing said casing against said limit means with said switch in open position, said switch being closable when a portion of said casing adjacent said switch is pressed toward said base; and razor blade positioning means. 90
13. A razor blade sharpener comprising: a base; electromagnetic means supported by said base; vibratory sharpening means adapted to be actuated by said electromagnetic means; limit means connected to said base; a casing; electrical connections to said electromagnetic means, including a switch, said switch comprising a pair of springs extending along opposite sides of said casing and normally resiliently pressing said casing against said limit means, said springs having adjacent ends having cooperating switch parts, said switch parts being away from switch closing position when said casing is normally resiliently pressed against said limit means, said adjacent ends and switch parts being pressed together to close said switch when a portion of said casing adjacent said adjacent ends is pressed toward said base; and razor blade positioning means. 95
14. A razor blade sharpener comprising: a base; electromagnetic means supported by said base; vibratory sharpening means adapted to be actuated by said electromagnetic means; limit means connected to said base; a casing; electrical connections to said electromagnetic means, including a switch adjacent one side of said casing and lead-in wires adjacent the opposite side of said casing, part of said switch comprising a spring extending along a side of said casing between said one and opposite sides of said casing and connected to one of said lead-in wires and normally resiliently pressing said casing against said limit means with said part of said switch away from switch closing position, said switch being closable when a portion of said casing adjacent said switch is pressed toward said base; and razor blade positioning means. 100
15. A razor blade sharpener comprising: a base; electromagnetic means supported by said base; vibratory sharpening means adapted to be actuated by said electromagnetic means; limit means connected to said base; a casing; electrical connections to said electromagnetic means, including a switch, said switch comprising a pair of springs extending along opposite sides of said casing and normally resiliently pressing said casing against said limit means, said springs having adjacent ends having cooperating switch parts, said switch parts being away from switch closing position when said casing is normally resiliently pressed against said limit means, said adjacent ends and switch parts being pressed together to close said switch when a portion of said casing adjacent said adjacent ends is pressed toward said base; and razor blade positioning means. 105
16. A razor blade sharpener comprising: a base; electromagnetic means supported by said base; vibratory sharpening means adapted to be actuated by said electromagnetic means; limit means connected to said base; a casing; electrical connections to said electromagnetic means, including a switch, part of said switch comprising a spring normally resiliently pressing said casing against said limit means with said part of said switch held away from switch closing position, said switch being closable when a portion of said casing adjacent said switch is pressed toward said base; and razor blade positioning means. 110
17. A razor blade sharpener comprising: a base; electromagnetic means supported by said base; vibratory sharpening means adapted to be actuated by said electromagnetic means; limit means connected to said base; a casing; electrical connections to said electromagnetic means, including a switch, part of said switch comprising a spring extending along a side of said casing between said one and opposite sides of said casing and connected to one of said lead-in wires and normally resiliently pressing said casing against said limit means with said part of said switch away from switch closing position, said switch being closable when a portion of said casing adjacent said switch is pressed toward said base; and razor blade positioning means. 115
18. A razor blade sharpener comprising: a base; electromagnetic means supported by said base; vibratory sharpening means adapted to be actuated by said electromagnetic means; limit means connected to said base; a casing; electrical connections to said electromagnetic means, including a switch, part of said switch comprising a spring normally resiliently pressing said casing against said limit means with said part of said switch held away from switch closing position, said switch being closable when a portion of said casing adjacent said switch is pressed toward said base; and razor blade positioning means. 120
19. A razor blade sharpener comprising: a base; electromagnetic means supported by said base; vibratory sharpening means adapted to be actuated by said electromagnetic means; limit means connected to said base; a casing; electrical connections to said electromagnetic means, including a switch, part of said switch comprising a spring extending along a side of said casing between said one and opposite sides of said casing and connected to one of said lead-in wires and normally resiliently pressing said casing against said limit means with said part of said switch away from switch closing position, said switch being closable when a portion of said casing adjacent said switch is pressed toward said base; and razor blade positioning means. 125
